HERSCHEL E. CHASE, OF SYRACUSE, NEW YORK, ASSIGNOR TO UNITED STATES
HOFFMAN MACHINERY COMPANY, OF SYRACUSE, NEW YORK, A CORPORATION
OF DELAWARE.

GARMENT-PRESS.

1,395,667.

Specification of Letters Patent.

Patented Nov. 1, 1921.

Application filed May 11, 1920. Serial No. 380,683.

To all whom it may concern:

Be it known that I, HERSCHEL E. CHASE, of Syracuse, county of Onondaga, and State of New York, have invented new and useful 5 Improvements in Garment-Presses, of which the following, taken in connection with the accompanying drawings, is a full, clear, and exact description.

This invention relates to certain improvements in garment pressing machines in which the garment under treatment is subjected to moisture, pressure and heat in one and the same operation, the moisture being supplied in the form of steam from an external source for softening and sterilizing the fabric and rendering it more pliable and susceptible to shaping and also for restoring the nap, while the mechanical pressure and heat serve, respectively, to shape, fix the 10 shape and to dry the garment so that it may be put on and worn with safety immediately following such operation.

I am aware that machines of this character are now in extensive use in which the 15 excess or waste steam is withdrawn from the machine by steam-induced suction incorporated in the machine and deriving its power from the same source which supplies the moisture and heat, and while my invention 20 is for a similar purpose, its specific object is to produce this suction by suitable means operated by one of the moving parts, such as the press head of the machine, so as to conserve the use of steam or other external 25 power and thereby further reduce the cost of operation.

Another object is to assure the operation 30 of the suction device coincidently of the separation of the pressing elements in releasing the garment for removal or inspection.

Other objects and uses will be brought out in the following description.

In the drawings—

Figure 1 is a top plan, partly in section 35 and partly broken away, of a garment pressing machine embodying one form of my invention.

Fig. 2 is an enlarged transverse vertical 40 sectional view of the buck and head taken on line 2—2, Fig. 1.

Fig. 3 is a side elevation, partly in section 45 and partly broken away, of the same machine.

As illustrated, this machine comprises a

main supporting frame —1— upon which 55 is mounted a relatively stationary buck —2— and a movable press head —3— having a rearwardly extending arm —4— which is fulcrumed at —5— upon upwardly extending arms —6— of the main supporting frame 60 some distance to the rear of the pressing elements so as to leave a clear open space entirely around the buck for manipulation of the garment thereon.

The buck —2— is provided with a heating chamber —7— and a combined steam-distributing and suction chamber —8— having a perforated top —9— through which the steam may be admitted to the garment and withdrawn therefrom when it is desired to apply the steam to the garment from the under side.

Steam may be supplied to the chamber —7— from any available source, not shown, for heating purposes through a pipe —10— 75 and the water of condensation may be drawn off through a drain pipe —11—.

The steam for moistening purposes may be admitted from the same source to the distributing chamber —8— through a pipe 80 —12— communicating with said chamber, as shown more clearly in Fig. 2, and controlled by a valve —13—.

When it is desired to moisten the garment from the bottom, the valve —13— is opened 85 for an instant only to supply the necessary blast of steam through the perforated plate —9—, thereby allowing the steam to come into contact with the garment.

A suction pipe —14— is also connected at 90 one end to the chamber —8— and has its other end connected to a suction pump —15— of the reciprocating piston type located at the rear of the machine and adapted to be operated by the movement of the press head —3— to and from the buck.

For this purpose, the lower end of the cylinder —16— of the pump is pivoted at 100 —17— to the lower rear portion of the frame —1— to rock forwardly and rearwardly, while the upper end of the piston rod as —18—, is pivotally connected at —19— to the rear end of the rock arm —4—.

The pipe —14— is preferably connected to the upper end of the cylinder —16— and 105 is provided with a check valve —20— to allow the steam to be drawn into the cylinder as the piston is moved downwardly by

the upward movement of the head and to prevent the back-flow of the steam when the operation of the piston is reversed.

A discharge pipe —21— is also connected to the upper end of the cylinder —16— to allow escape of steam or water of condensation as the piston is moved upwardly by the downward movement of the press head, or before said movement if the steam or water is present in the cylinder.

The purpose in pivotally supporting the cylinder is to allow it to conform to the changing positions of the piston rod —8—, as the press head is rocked in reverse directions, the pipe —14— being flexible to allow rocking movement of the cylinder without overstraining the connections of said pipe with the buck and cylinder.

The exhaust pipe —21— is also provided with check valve —22— to allow the exit of the steam and water of condensation and to prevent back-flow of the same into the cylinder, and at the same time affording relief against compression of the steam or water by the upward movement of the piston, the pipe —21— being also flexible to allow backward and forward movement of the cylinder without overstraining its connections.

The press head —3— is shown as provided with a steam-distributing chamber —23— having a perforated bottom —24— through which the steam may also be admitted to the garment when it is desired to apply moisture from the upper side, in which case the steam is supplied to said chamber through a pipe —26— having a valve —27— by which it may be controlled, preferably by the introduction of a short blast at a time, the steam being caused to spread out over practically the entire area of the perforated plate —24— by its own expansive force aided by contact with the baffle plate —28— within said chamber.

This chamber —23— also constitutes a suction chamber when the valve —27— is closed and is connected by a pipe —14'— to a separate pump —15'— similar to the pump —15—, in that it is of the piston type having a cylinder —16'— and a piston rod —18'—, the cylinder being pivoted at its lower end at —17'— to the frame —1— and having the upper end of its piston rod pivotally connected to the rear end of the arm —4— in a manner similar to that shown in Fig. 3 for the pump —15—.

The upper end of the cylinder —16'—, like the cylinder —16— is provided with an exhaust or discharge pipe —21'— which, together with the discharge pipe —21—, merges into a single flexible exhaust pipe —29— which may lead into a soil pipe or to the exterior of the building so as to prevent the escape of the steam into the room.

The means for operating the press head

is similar to that set forth in the patent to Spencer, 1,164,616, December 14, 1915, in that it is forced to its pressing position by a pedal lever —30— and toggle levers —31— and is retracted by means of a spring —32— and counterweight —33— when the pedal lever is released, said head being also provided with a handle —34— by which it may be operated if desired.

The suction pipe —14'—, like the suction pipe —14—, is provided with a check valve —20'— operating in the same manner as the pipe —20—, the check valve —22— serving to control the exits from both cylinders.

In operation, assuming that the press head is raised away from the buck, the garment is first spread out upon the upper surface of the buck and properly arranged for pressing, after which the head is brought to its pressing position and locked, whereupon a blast of steam is introduced either through the buck or head by opening the corresponding valve for an instant only, thus bringing the steam into contact with the garment in sufficient quantities to properly moisten the same without saturation even though a part of the steam thus introduced into the head or buck may find exit through the conduits —14— or —14'— and exhaust conduits —21— and —21'—, which, in some instances, is an advantage because it further prevents oversaturation of the garment in case the steam should be highly charged with moisture.

During this pressing operation, the moisture of the steam renders the garment soft and pliable, while the mechanical pressure gives it the desired shape and together with the heat fixes such shape, while the heat of both the buck and press head tends to dry the garment.

Immediately following this pressing operation, the pedal lever is released allowing the spring —22— and counterweight —33— to raise the head and depress the pistons of both pumps simultaneously which produces a partial vacuum in the upper end of each cylinder, thereby withdrawing the steam from both the buck and head into the cylinder and allows it to escape through the discharge conduits —21— and —21'—, or if it is not completely expelled from the cylinder, or any water of condensation remains therein, the upward movement of the piston by the depressing of the head forces such steam or water of condensation from said cylinders into their respective exhaust conduits —21— and —21'—.

This is a particularly simple means of withdrawing the excess steam from the garment and also from the pressing elements, and at the same time effects a more rapid drying and cooling of the garment, thereby conserving the steam and to that extent reduces the cost of operation.

It is also evident that the same suction device may be used for removing dust and vapor from the garment by simply raising and lowering the head while the garment is on the buck.

The important advantage, however, in operating the suction device during the opening and closing movement of the movable pressing element is that it takes the moisture away from the padded surfaces of the pressing elements and avoids any possibility of overdrying the garment by reason of the fact that it is impossible to operate the suction device while the pressing elements are together upon the garment, or, in other words, prevents the suction during the pressing operation and permits it only when said elements are separated.

What I claim is:

- 20 1. In a garment pressing machine the combination with coacting pressing elements movable one in relation to the other, means for applying steam to the garment between said elements, and means for withdrawing the steam only when the pressing elements are open, said last named means comprising a suction pump actuated by the movable pressing element when moved away from the other pressing element.
- 25 2. In a garment pressing machine, co-operative pressing elements, one of which is movable toward and from the other, the movable pressing element being provided
- 30 with a steaming chamber having an opening through its pressing face for admitting steam to the garment, a steam supply pipe leading to said chamber and provided with a valve for controlling the passage of steam therethrough, a suction pump actuated by the movable pressing element during its separation from the other pressing element and connected to said chamber for withdrawing the steam therefrom only when the pressing elements are being separated.
- 35 3. In a garment pressing machine, co-operative pressing elements movable one in relation to the other, each of said pressing elements being provided with a steaming chamber having an opening through its pressing face for admitting steam to the garment, steam pipes leading to said chambers and provided with valves for controlling the passage of steam therethrough, suction pumps actuated by the movable pressing element when moved away from the other pressing element and connected to said chambers for withdrawing the steam therefrom only when the pressing elements are separated.
- 40 4. In witness whereof I have hereunto set my hand this tenth day of May, 1920.
